UNITED STATES PATENT OFFICE.

BYRON J. PEPPER, OF FORT WAYNE, INDIANA.

HEAT-TRANSFER DEVICE.

Application filed January 27, 1925. Serial No. 5,098.

My invention relates to heat transfer devices especially of the type commonly used in subjecting liquids to Pasteurizing or other processes involving heat interchange.

Among the functional advantages of the invention over the prior art may be enumerated:

First, securing substantially constant flow through the device independent of the pressure or head of the liquid delivered thereto.

Second, acceleration of the incoming liquid to substantially the rotational speed of the mass of liquid under treatment before such incoming liquid is permitted to join the main mass of liquid.

Third, removal of the treated liquid from the rotating mass without generating foam or air bubbles.

Among the advantages of the structural embodiment shown may be enumerated:

First, quick removability of the bearings.

Second, improved clamping means for the heads carrying the bearings.

Third, interchangeable intake connections for convenience in installation.

Fourth, housing the intake control mechanism and the thermostat in the delivery passage inside the rotating elements to cut down the overall length of the complete device.

Further objects and advantages of the invention will become apparent as the description proceeds.

In the accompanying drawings:

Fig. 1 is a side elevation, with the outer casing partially in vertical longitudinal section, of a heat transfer device according to the invention.

Fig. 2 is a horizontal section of the same on line 2—2 of Fig. 1.

Fig. 3 is a transverse section on line 3—3 of Fig. 2.

Figs. 4 and 5 are a detailed section and end elevation of the clamping means for the heads.

Fig. 6 is a perspective detail of the constant flow valve.

Figs. 7, 8 and 9 are diagrams indicating the action of the exit disc.

In the embodiment of the invention selected for illustration, a suitable base 10 is provided with feet 12 and carries side standards 14 fastened in place by stud screws 16 passing up through base 10 from below. The standards terminate in aligned trunnions 18 receiving the duplicate bosses 20 of a ring casting partitioned to define a pressure

steam chest 22 and an exhaust chest 24, both of annular shape. Duplicate stationary end castings 26 are bolted to opposite ends of the body casting for detachably supporting an intake head 28 and a delivery head 30, which I have illustrated as duplicates.

Duplicate inner races 32 and 34 are clamped in place on heads 28 and 30 between shoulders formed on said heads, and retaining shoulders on an inlet cap 36 and a delivery cap 38 threaded in place on said heads. The holder 40 for the outer race at the discharge end is provided with an annular groove to receive rubber ring 42, and an inner annular plate portion 44 forming an abutment for the outer ball race which may be held in place by a suitable retainer 46.

The inner edge of plate 44 carries a short cylindrical lip 48 entering a suitable groove in the delivery cap 38.

In addition to parts duplicating those of the outer race holder for the delivery end, the outer race holder for the intake end includes an accelerator comprising a cylindrical portion 50 continued by a conical portion 52 terminating in an inturned lip 54. The inlet cap 36 is a cylindrical tube having an external flange defining an annular groove 56 and a plurality of radial discharge ports 58.

The entering liquid issuing from ports 58 impinges in the first instance on the conical portion 52 of the accelerator and picks up the rotary speed thereof while traveling across the cylindrical portion 50 and before issuing from the radial discharge openings 60 to join the whirling mass of liquid, which preferably lies at substantially the radial distance indicated by the dotted line at 62.

Rubber rings 42, when the parts are not rotating, have a substantially circular cross section and extend radially outward slightly beyond the periphery of holders 40 to make light surface contact with the end lip of casting 64, lying substantially tangent thereto. Under the centrifugal force of high speed rotation the circular cross section of the ring is distorted and flattened against casting 64 to form a firm mechanical connection and a tight seal between holder 40 and casting 64. Thus when the parts are not rotated, heads 28 and 30 and the rings 40 carried thereby, can be readily lifted out and slipped into place although the mechanical connection between them, when the parts are rotated and such connection is necessary,

is entirely adequate to guide and support castings 64.

The entering liquid issuing from ports 58 impinges in the first instance on the conical portion 52 of the accelerator and picks up the rotary speed thereof while traveling across the cylindrical portion 50 and before issuing from the radial discharge openings 60 to join the whirling mass of liquid, which preferably lies at substantially the radial distance indicated by the dotted line at 62.

The central rotating casting 68 has radially corrugated flanges 70 at its ends permanently united as by welding, brazing, soldering, or the like, with the ends of the radially corrugated liner 72 constituting the heating drum proper. Intermediate its ends it has a plurality of similar sets of projections 74 terminating radially short of the inner ends 20 of the convolutions of drum 72 to leave clearance at 76 for axial flow of gaseous heating fluid, and cut back at 77 at intervals in such a way as to let condensation travel along the casting in a circuitous path. Suitable impulse channels 78 in an outwardly extending flange on body 68 receive the fluid issuing at high velocity from nozzles 80 in the stationary body, and at the other end radial ports 82 deliver the fluid which has imparted first, its kinetic energy to the body 68 to rotate the same, and second, its sensible and preferably also its latent heat of vaporization to the drum 72. The inner ends of channels 78 are preferably set in a 35 little radially by forming an annular projection 79, to prevent condensation from returning through the channels.

Ports 82 open into exhaust chamber 24 communicating freely with the annular clearance 84 between castings 26 and 64 at one end, the similar clearance at the other end receiving such slight leakage as may occur from the open joints around nozzles 80. The chamber also opens at 81 into a 45 horizontal exhaust chamber 86 at the bottom of the stationary body, from which any suitable discharge means such as pipe 88 provides an exit, and both end clearances also open into chamber 86 at 87. The chamber 24 is preferably provided with a relief valve 89, for safety in case other outlet means should be obstructed.

Inside the rotating parts, the liquid delivered from the accelerator 60 accumulates in the annular clarification chamber 90, passes axially over drum 72, and is accumulated again in chamber 92 at the other end.

Delivery cap 88 carries a flange 94 perforated by radial ducts 96. The outer periphery of the disc is grooved at 98 and the edges of the groove rounded. Fig. 7 indicates diagrammatically the condition just before chamber 92 has filled up and delivery begins. The whirling mass of liquid is indicated at 100. A slight rise of the liquid level will

bring the surface into contact with the edges of the disc 94 and the liquid will almost instantaneously move to the position shown in Fig. 8 with the cumuli 102 riding on either side of the disc, groove 98 filled with liquid and liquid moving rapidly inward in the ducts 96. I believe the explanation of this phenomenon to be as follows: The liquid in contact with the smooth peripheral surface of disc 94 will be rapidly slowed down as to its rotational velocity by friction at its surface of contact with the stationary disc. The portion of the liquid thus retarded is no longer capable of staying out away from the center and is rapidly pushed in by the other portions still moving at full velocity. Thus the groove is kept filled and the outer surface of the disc continuously wiped by the inward protuberance at 102. The centripetal action thus generated is so powerful that at normal rates of flow through the machine Fig. 8 will immediately give place to the conditions indicated in Fig. 9, with the liquid level moved back substantially to that shown in Fig. 7, the cumuli at 102 maintaining a seal as long as flow continues in sufficient quantities to keep the liquid level from receding beyond that shown in Fig. 9. The liquid delivered at the inner ends of passage 96 comes through entirely free from any foam or froth which might be generated by abrupt interruption of the movement as by an ordinary scoop. As long as the cumuli 102 maintain the seal, the gas in contact with the liquid mass 100 has no access to the discharge passages and the gentle gradual retardation of the liquid moving up into the cumuli and into passage 96 does not whip the surface or cause any material turbulence.

It is an interesting coincidence that the rotational speed of a machine of given size must be increased when the rate of flow through it is increased in order to treat the liquid properly, and because the ejecting action on the disc is a function of the rotational speed, no material change in the capacity of passages 96 need be made in operating a machine over substantially the entire range of loads of which it is otherwise capable.

The liquid delivered at the inner ends of passages is treated and ready to leave the device. It is also desirable to control the steam flow as a function of the temperature of the liquid leaving the device. I have illustrated a thermostat comprising an annular chamber at 104 for the temperature sensitive fluid. To cut down on the overall length of the machine I form an inwardly extending cap 106 and let the thermostat chamber project axially into the vacant and otherwise useless space at the center of the device. In this way a saving in length equal to the distance the thermostat is telescoped into the tube is effected. The thermostat as a whole

is fastened in place on head 30 by means of a threaded connection at 108 and comprises the chamber 104 and a storage chamber at 110 from which a connecting tube 112 extends to a suitable steam control valve. As the general type of thermostat involved is old and well known in the art and the advantages of the particular form of thermostat I prefer to employ are made the subject 5 matter of my co-pending application, Serial No. 5,754, filed Jan. 30, 1925, further detailed description of the thermostat is deemed unnecessary.

Although the exit disc 94 will satisfactorily take care of a wide variation in rate of flow, and the automatic thermostat control will provide the necessary variations in speed of rotation and heat supply, it is preferable in practice to operate the machine at 15 a substantially constant load either as large as it can properly handle for the sake of capacity, or that at which it functions most efficiently for the sake of economy in power. Furthermore, where the machine is to receive 20 its supply from a large and rather deep container located only slightly above the level of the machine, the effective head on the inlet to the machine will decrease as the container is emptied, to a very small fraction of the 25 initial pressure when the container is full.

Valve 114 slides freely in inlet cap 36, being urged inward by the pressure of the incoming liquid and outward by the varying tension of a suitable coil spring 116. At the 30 minimum supply pressure at which the machine is intended to operate it preferably occupies the position shown in Fig. 2 with substantially the entire area of groove 56 open through the valve ports to receive the liquid. The valve ports comprise a plurality of tapered slots, in this instance four, flaring at their ends as at 120. A narrow peripheral connection at 124 unites that portion of the valve outside the diaphragm 126 with the cup portion 128 receiving spring 116. It will be apparent that any increase 35 of pressure at 130 will push the valve to the right and cover a portion of groove 56. By properly shaping the slots 118 according to curves that can be computed with mathematical precision, automatic control of the flow to remain substantially constant over a predetermined range of pressures can be easily obtained. An opening at 132 is provided to prevent disturbance of the automatic action by the pressure of air which would otherwise be stored in the cavity housing spring 116.

Each of the heads 28 and 30 is provided 40 with two diametrically opposed bosses 134 bifurcated to receive suitable quick detachable clamping devices. I have illustrated housing 136 threaded into suitable apertures in castings 26. Each housing receives a 45 spring 136 encircling a bolt 140 shouldered

at 142 to receive the thrust of the spring and again at 144 to constitute a positive stop. A handle 146 is threaded on the projecting end of the bolt 140 and has a head 148 which in the position shown in full lines in Fig. 70 5 overlies the bifurcation of boss 134 and in the dotted line position fits between said bifurcations to permit removal of the head. In the locked position, the engagement between head 148 and its boss is intended to 75 bring shoulder 144 snug against its abutment. Whenever wear on the parts develops material looseness the play can be taken up by loosening lock nut 150 and threading the handle down on the bolt. When the head 80 is not in place spring 138 pulls the lever against the casing 136 so that it will not dangle loosely and be in the way in assembling the parts.

Each head is preferably provided with a 85 suitable sight-feed oiling device 152 to deliver a suitable supply of lubricant to the bearings.

When the device is to be cleaned or inspected, both heads can be lifted out of place 90 very quickly. For a thorough cleaning, one of the heads may be replaced by a solid plug, and the machine, with its axis turned vertical, can be filled with a cleaning solution and let stand indefinitely. In this position 95 it can also be conveniently scrubbed and swabbed out.

Trunnions 20 permit this manipulation of the device without in any way interfering with the connections for the steam supply. The duplicate trunnions permit such connection to be conveniently made at either side off the machine, one trunnion receiving the steam supply pipe 154 carrying flange 156 clamped in place against packing 158 by a 100 retaining ring 160 provided with a suitable lock nut 162; and the other trunnion receiving a simple plug 164. When the machine is in operation trunnions 20 will preferably 105 be clamped against rotation by suitable manually operated clamps 166 which may readily be relieved to permit tilting of the machine when that is desired.

Without further elaboration, the foregoing will so fully explain the gist of my invention, that others may, by applying current knowledge, readily adapt the same for use under various conditions of service, without eliminating certain features which may properly be said to constitute the essential items of novelty involved, which items are intended to be defined and secured to me by the following claims.

I claim:

1. A liquid treating device comprising a 125 rotating drum, an annular accelerator in the intake end of said drum, a stationary axial inlet tube telescoped inside said accelerator and extending axially inward beyond the same, ports in said tube at the inner end of 130

said accelerator to deliver liquid thereto, a constant flow valve sliding in said tube over said ports, and a positioning spring housed in the inner end of said tube and acting on 5 said valve.

2. A liquid treating device comprising a 10 rotating drum, a stationary inlet, and an accelerator comprising an annular shell rotating with the drum and positioned to receive the liquid from said inlet, said accelerator having delivery ports opening radially outward in the drum and offset axially from the plane of the inlet.

3. A liquid treating device comprising a 15 rotating drum, a stationary inlet, and an accelerator comprising an annular shell rotating with the drum and positioned to receive the liquid from said inlet, and said accelerator having delivery ports opening radially outward in the drum.

4. A liquid treating device comprising a 20 rotating drum, a stationary inlet, and an accelerator comprising an annular shell rotating with the drum and positioned to receive the liquid from said inlet, said accelerator comprising a hollow cone to receive liquid from the inlet at a small radius and convey it out and axially to one side, a cylinder continuing the base of said cone to convey the liquid further in an axial direction, and ports at the end of said cylinder remote from said cone.

5. A discharge means for taking liquid 25 from the inside of a hollow rotating mass comprising a disc having its periphery defined by surfaces of revolution, said disc having radial exit ports opening at said periphery.

6. A discharge means for taking liquid 30 from the inside of a hollow rotating mass comprising a smooth disc having a grooved periphery, and radial ports leading inward from the bottom of said groove,

7. A discharge means for taking liquid 35 from the inside of a hollow rotating mass, comprising a stationary body having a radially extending passage with an open outer end, forming means for retarding the liquid adjacent said end without turbulence to generate an inwardly extending annular protuberance covering and sealing said open end.

8. A discharge means for taking liquid 40 from the inside of a hollow rotating mass, comprising a stationary body having a radially extending passage with an open outer end, forming means for retarding the liquid adjacent said end to generate an inwardly extending annular protuberance covering and sealing said open end.

9. A liquid treating device comprising a 45 stationary casing, a rotary casing inside the same, anti-friction bearings having races at the ends of said casings, and mechanical connections including a resilient ring between

the rotary casing and the adjacent races of the anti-friction bearings held in assembled relation by centrifugal force and resiliently disconnected when rotation ceases.

10. A liquid treating device comprising a 50 stationary casing, a rotary casing inside the same, anti-friction bearings having races at the ends of said casings, and mechanical connections including a resilient ring between the rotary casing and the adjacent 55 races of the anti-friction bearings held in assembled relation by centrifugal force.

11. A liquid treating device comprising a 60 stationary casing, a rotary casing inside the same, anti-friction bearings at the ends of 65 said casings, having inner and outer rings and an anti-friction rotary connection between said rings, said rotary casing having a ring at each end telescoped with one of the rings of the bearings, an annular groove 70 in the outer periphery of the inner one of said telescoped rings, the opposing surface of the other ring being flat, and a resilient rubber ring seated in said groove and adapted to expand centrifugally into firm contact with the encircling ring when the parts are rotating.

12. A liquid treating device comprising a 75 stationary casing, a rotary casing inside the same, anti-friction bearings at the ends of 80 said casings, having inner and outer rings and an anti-friction rotary connection between said rings, said rotary casing having a ring at each end telescoped with one of the rings of the bearings, and means seated on 85 one of said telescoped rings and adapted to expand centrifugally into firm contact with the other ring when the parts are rotating.

13. A liquid treating device comprising a 90 stationary outer casing, a rotary inner casing, heads on the end of said outer casing, anti-friction bearings on said heads supporting said inner casing, quick detachable connections between said stationary casing and 95 said heads, and detachable connections between said bearings and said rotary casing.

14. In a liquid treating means having a 100 stationary casing, heads on the ends thereof, and a rotary casing journaled on said heads and on said stationary casing, two diametrically opposed bifurcated bosses on each head, and quick detachable connections cooperating with said bosses to clamp said heads in place, each connection comprising a bolt axially slidable on said stationary casing and 105 passing through the bifurcation, a handle on the outer end of said bolt rotatable about the axis thereof to overlie said bifurcations or to clear them, a spring acting axially on said bolt to press inwardly on said handle against the bifurcations, shoulders on said bolt and its support limiting outward movement of the bolt, and axial adjustment means 110 between bolt and handle to bring said shoulders snug when the head is clamped in place.

15. In a liquid treating means having a stationary casing, and heads on the ends thereof, bifurcated bosses on each head, and quick detachable connections co-operating with said bosses to clamp said heads in place, each connection comprising a bolt axially slidable on said stationary casing and passing through the bifurcation, a handle on the outer end of said bolt rotatable about the axis thereof to overlie said bifurcations or to clear them, a spring acting axially on said bolt to press inwardly on said handle, shoulders on said bolt and its support limiting outward movement of the bolt, and axial adjustment means between bolt and handle to bring said shoulders snug when the head is clamped in place.

16. A liquid treating device comprising a relatively stationary casing, a rotor telescoped inside said casing, said casing having chambers and passages to receive fluid for driving and heating said rotor, hollow trunnions pivoting said casing on an axis at an angle to the axis of rotation of said motor, both trunnions opening into the same chamber in said casing, fluid supply means connected through one trunnion, a plug in the other trunnion, said rotor having open ends, and detachable heads carried by said casing and closing the ends of said rotor.

17. A liquid treating device comprising a relatively stationary casing, an open-ended rotor telescoped inside said casing, means on the outside of said rotor and inside of said casing for driving and heating said rotor, heads detachably mounted on said casing and covering the open ends of said rotor, and intake and outlet means for liquid inside said rotor carried by said heads and telescoped in said rotor, said intake means including a cylindrical constant flow valve housed in said rotor, and said outlet means including a tubular thermometer bulb forming an exit passage and telescoped in said rotor, a reverse flow tubular casing housing said bulb and conveying liquid from the end of said rotor to the inner end of the bulb, and a collecting disc at the outer end of said reverse flow casing.

18. A liquid treating device comprising a relatively stationary casing, an open ended rotor telescoped inside said casing, means on the outside of said rotor and inside of said casing for driving and heating said rotor, heads detachably mounted on said casing and covering the open ends of said rotor, and intake and outlet means for liquid inside said rotor carried by said heads and telescoped in said rotor, said intake means including a cylindrical constant flow valve housed in said rotor, and said outlet means including a tubular thermometer bulb forming an exit passage and telescoped in said rotor, and a reverse flow tubular casing housing said bulb and conveying liquid from

the end of said rotor to the inner end of the bulb.

19. A liquid treating device comprising an open-ended rotor, and intake and outlet means for liquid telescoped inside said rotor, said intake means including a cylindrical constant flow valve housed in said rotor, and said outlet means including a tubular thermometer bulb forming an exit passage and telescoped in said rotor, and a reverse flow tubular casing housing said bulb and conveying liquid from the end of said rotor to the inner end of the bulb.

20. A liquid treating device comprising an open-ended rotor, and intake and outlet means for liquid telescoped inside said rotor, said intake means including a cylindrical constant flow valve housed in said rotor, and said outlet means including a tubular thermometer bulb forming an exit passage and telescoped in said rotor, a reverse flow tubular casing housing said bulb and conveying liquid from the end of said rotor to the inner end of the bulb, and collecting means at the outer end of said reverse flow casing.

21. A liquid treating device comprising an open-ended rotor, and intake and outlet means for liquid telescoped inside said rotor, said intake means including a cylindrical constant flow valve housed in said rotor, and said outlet means including a tubular thermometer bulb forming an exit passage and telescoped in said rotor, a reverse flow tubular casing housing said bulb and conveying liquid from the end of said rotor to the inner end of the bulb, and collecting means at the outer end of said reverse flow casing.

22. A liquid treating device comprising an open-ended rotor, and intake and outlet means for liquid telescoped inside said rotor, said intake means including a cylindrical constant flow valve and said outlet means including a tubular thermometer bulb forming an exit passage, and a reverse flow tubular casing housing said bulb.

23. A liquid treating device comprising an open-ended rotor, and intake and outlet means for liquid telescoped inside said rotor, said intake means including a cylindrical constant flow valve housed in said rotor, and said outlet means including a tubular thermometer bulb forming an exit passage.

24. A liquid treating device comprising an open-ended rotor, and intake and outlet means for liquid inside said rotor, said intake means including a cylindrical constant flow valve housed in said rotor.

25. A liquid treating means comprising a casing, a rotor telescoped therein, and means on the outside of the rotor and on the inside of the casing for driving said rotor including nozzles on the casing and impulse receiving passages on the rotor to receive fluid from said nozzles, said rotor having two walls defining an annular cham-

- ber with a substantially cylindrical outer wall, and an annular protuberance projecting inward slightly from said wall, said passages opening through said protuberance.
- 5 26. In a liquid treating device having a revolving drum mounted to rotate at high speed and maintain a whirling mass of liquid in annular shape therein and having an outlet tube, means for transferring liquid
- 10 from the moving mass to the outlet tube comprising a stationary disc having a radial passage therethrough communicating with the outlet tube and extending to the periphery of the disc.
- 15 27. In a liquid treating device having a

revolving drum mounted to rotate at high speed and maintain a whirling mass of liquid in annular shape therein and having an outlet tube, means for transferring liquid from the moving mass to the outlet tube comprising a stationary disc having radial passages therethrough communicating with the outlet tube and extending to the periphery of the disc, the peripheral wall of said disc having a groove extending circumferentially thereof.

20 In witness whereof, I hereunto subscribe my name this 23rd day of January, 1925

25 BYRON J. PEPPER.
